CONTAINER CAPPING STRUCTURE

Edward M. Enkur, Babylon, N. Y., and Leo F. Pahl and Louis L. Lauve, Baltimore, Md., assignors to Crown Cork & Seal Company, Inc., Baltimore, Md., a corporation of New York

Application November 6, 1944, Serial No. 562,110, which is a division of application Serial No. 351,004, August 3, 1940. Divided and this application December 17, 1945, Serial No. 635,552

3 Claims. (Cl. 226—30)

1

The present invention relates to container capping structures and is a division of our application for Container Capping Apparatus Serial No. 562,110, filed November 6, 1944, and since issued as Patent Number 2,479,822, which in turn, is a division of our original application for Container Sealing Apparatus Serial No. 351,004, filed August 3, 1940, and since issued as Patent Number 2,433,549.

An object of the invention is to provide an efficient apparatus for applying a cap to a filled container and then moving the cap to sealed position without interference with the forward movement of the container.

The usual apparatus for applying caps to moving containers for subsequent sealing comprises a belt or the like which moves the filled containers beneath an inclined cap chute positioned at such height that the leading mouth portion of the advancing container will engage the depending or leading portion of the skirt of the downwardly inclined cap. The cap is then released from the cap chute and its trailing portion drops downwardly to a fairly levelled or applied position upon the container mouth.

It will be understood by those skilled in the capping art that the terms "levelled" or "applied," as used above and elsewhere in this specification refer to the position assumed by the cap on the container mouth by its weight alone. In such position, the cap will usually be slightly tilted due to the fact that some points, such as lugs or the like, on the skirt may be of smaller diameter than the outside diameter of the container mouth. However, when levelled upon the container, as is understood in the art, at least the lower edge of the cap skirt is aligned with the cap mouth, even though it may be tilted on the cap mouth.

The arrangement to control the cap during the above applying or levelling operation is of extreme importance because some difficulties are involved in handling the cap during such movement without losing complete control of it. Obviously, if control of the cap is lost during the so-called levelling action, the cap will slide, either forwardly or sidewise, off of the container, or it may move sufficiently far forward upon the mouth of the container that its skirt will not be in substantial circular alignment with the container mouth.

Another important feature of this mechanism of our invention is the provision of means to hold the cap upon the container until the subsequent sealing operation. In prior machines, after the cap has been applied or levelled, the container has carried it out of contact with the levelling

2

device and the cap and container move to the sealing device with the cap usually tilted at an angle. At the moment that the cap moves out of contact with the levelling device the latter slides off the trailing portion of the cap and the cap is apt to be tilted entirely off the container. Also, if a capping element of the endless belt or chain type is used, it is possible for an applied cap to be knocked off the container mouth when the leading edge of the cap comes into contact with the continuously moving belt, particularly if the cap is markedly tilted with respect to the container.

Our invention includes means to contact with the cap and firmly hold it upon the container from a time prior to the movement of the cap from the levelling device until it fully contacts with the sealing device.

The above improvement is of substantial value with any combination of levelling device and capping means and is of particular importance in that it removes difficulties heretofore encountered with endless belt capping devices. Endless belt capping devices have substantial advantages over other types due to the fact that containers may be presented to them in irregularly spaced relation. All other types of capping mechanisms require that containers be presented in exactly spaced or timed relation and in order to obtain this spacing, it is necessary to include a timing device. The use of timing devices is highly objectionable, since they intermittently stop the movement of the filled but uncapped containers and this frequently results in some of the container contents being spilled over the edge of the container mouth, which results in an undesirable condition.

In view of the above, it will be observed that the present invention is designed to so combine cap applying and sealing mechanisms that the caps will be (1) properly applied, (2) held in proper position until sealing; and (3) efficiently sealed upon the containers, all without interrupting the movement of the containers or requiring any timing devices to stop the filled containers.

In its present embodiment, the above-described holding mechanism includes a moving endless belt of bodily flexible material with which a cap applied to a container will contact before such cap leaves the control of the cap applying mechanism. The endless element will then further act to level the cap upon the container and will firmly hold it upon the container until the cap is moved to sealed position.

Another object of the invention is to provide

a capping mechanism of such construction that caps will not be marred and which will quickly and efficiently move the caps to sealed position.

It has heretofore been proposed to provide a sealing element comprising an endless chain formed of metal links and with a fabric or other bodily-flexible belt surrounding the metal chain to prevent caps being marred. It is necessary to have the metal chain driven at the same speed as the container supporting conveyor and if the fabric belt is not driven at the same speed, containers are apt to be tipped over or the caps thrown from the containers. In the prior arrangements, the fabric belt has been driven by surface contact with the metal belt but this arrangement has not been altogether satisfactory. By the arrangement of the present invention, the fabric belt is positively driven at the same speed as the metal chain.

Other objects and advantages of the invention will be apparent from the following drawings wherein:

Figure 1 is a side elevation of the machine;

Figure 2 is a top view of the machine;

Figures 3a and 3b taken together, comprise a longitudinal vertical sectional view through the container centering element and the capping element;

Figure 4 is a transverse vertical sectional view on the line 4—4 of Figure 3b, and

Figure 5 is a transverse vertical sectional view on the line 5—5 of Figures 2 and 3a.

In the following description of the invention, the apparatus is described as operating to apply and seal skirted caps to containers having a horizontally projecting shoulder or ring on their mouths, the cap skirt being sufficiently resilient that inwardly projecting lugs at the lower end of the cap skirt will engage beneath the container mouth shoulder when the cap is in sealed position. Such caps are provided with a sealing ring or disc on the under side of their top wall to bear upon the top edge of the container mouth to form an air-tight seal. It will be understood that the apparatus may be used with numerous other types of caps.

The construction and operation of the apparatus may be generally described as follows: Caps of the type described are placed in tray 22 with their skirts downward and are moved by hand to the inclined chute 23 of the tray so as to slide down upon the central portion of a continuously rotating disc 24. Rotation of the disc 24 in a counter-clockwise direction (Fig. 2) will cause the caps to be moved outwardly on the disc adjacent its periphery and through an outlet portion 25 to move upon a continuously moving endless chain 26 as described in said application Serial No. 351,004 which will conduct the cap to the left in Figures 1 and 2 between suitable lateral and top guiding members comprising the horizontal portion 27 of a cap passageway. This horizontal portion 27 terminates in an inclined chute 28 (Fig. 3b) forming a continuation of the cap passageway. Chute 28 is also provided with lateral and top guiding means and terminates in a cap applying or levelling mechanism 29 described in said original application.

Containers are delivered to the machine upon an endless conveyor 30 (Fig. 1) and move toward the left beneath the structure described immediately above to come in contact with the lowermost cap in the applying or levelling mechanism 29 as indicated in Figure 3b. At the time that the

container contacts with the skirt of the lowermost cap, the side walls of the container will be firmly engaged by opposed endless belts included in the container centering mechanism 31 described in detail in our divisional application for Container Handling Apparatus, filed of even date herewith. This mechanism will prevent the container from being tilted backwardly as it contacts with the lowermost cap in the chute 28.

Immediately before the cap moves out of contact with the applying mechanism 29, its upper surface will be engaged by an endless fabric belt 32 which further levels and holds the cap upon the container. Belt 32 moves along the outer surface of a capping element 33 of a construction generally similar to that disclosed in the Patent No. 2,256,415 issued September 16, 1941 on an application of Robert J. Stewart for Container Sealing Apparatus, element 33 being vertically adjustable to operate upon containers of various heights. In order that the fabric belt 32, which is of greater length than the inner capping belt 33, will move at substantially the same speed as the latter belt, a tensioned roller 34 is provided at the outer end of belt 32 and a weighted roller 35 is provided above capping element 33 to hold the upper run of fabric belt 32 in contact with the capping element 33.

Referring in detail to the construction of the apparatus, the machine preferably includes a table or base portion 40 which forms a continuous support for the endless container supporting conveyor 30.

The endless conveyor 30 for supporting container is of the construction best shown in Figure 3a. That is, it is formed of a plurality of pivotally connected links 45, each link including spaced ears 46 which have a plate 47 of substantially greater width than the link integrally formed thereon. The upper run of the conveyor 30 is adapted to have the outer edges of its plates 47 supported upon the inwardly projecting and horizontal portions 48 of angle irons which are suitably spaced to form a channel 49 extending along the table or base 40.

Referring to Figure 1, a motor 50 and a speed reducer 51 including a driven shaft 52 are supported upon the under side of the table 40. The driven shaft 52 of the speed reducer is provided with a small sprocket 53 which drives a sprocket chain 54 also encircling a sprocket 55 fixed to a shaft 56 journalled in the outfeed end of the table 40. The links of the container supporting conveyor 30 move about a sprocket wheel secured to shaft 56.

In order to support the various mechanisms which apply caps and seal them upon the containers at a suitable height above the container supporting element 30, the machine includes a longitudinally extending superstructure 57 shown in Figures 1 and 2 and including spaced bars 58 extending from the infeed end of the apparatus to the capping mechanism, while a plate element 59 comprises the superstructure for the capping mechanism. The superstructure 57 is supported above the table 40 by means of pairs of heavy links 61, 62 and 63 spaced from the outfeed to the infeed end of the machine, each pair of links comprising a link on each side of the supporting table and superstructure. As best shown in Figure 3a, the links 61 are pivotally mounted at their lower ends on a shaft 65 hereinafter described which is provided adjacent the outfeed end of the machine. As shown in Figure 3a, the lower ends of the links 62 are journalled

on a pin 66 extending through the side walls of the table 40, while as best shown in Figure 1, the links 63 are pivotally mounted at their lower ends upon a shaft 67 adjacent the infeed end of the machine. The upper ends of the links 61 (Fig. 3a) are pivotally supported upon a shaft 68 journalled in the superstructure plate 59. Referring to Figure 3b, the upper ends of the links 62 are pivotally connected to pins 69 extending through plate 59 while, as shown in Figure 1, the links 63 are pivotally mounted on brackets 65 secured to the superstructure bars 58.

It will thus be observed that the links 61 to 63 support the superstructure in parallel relation with the upper surface of the table 40.

In order that the superstructure 57 may be supported at a fixed height and its height adjusted with respect to base 40, the structure shown in Figures 3a and 5 is provided. This construction is similar to that disclosed in said Stewart patent and comprises a pair of rotatable threaded shafts 71 and 72 extending between the base or table and the superstructure. The upper and threaded ends of the shafts 71 and 72 are threaded in collar nuts 73 and 74, respectively, fixed to the ends of a pin 75 which is journalled in the superstructure plate 59. The lower and unthreaded ends of the shafts 71 and 72 are journalled in upward extensions 76 of a bracket 77 which extends beneath table 40. Bracket 77 is pivotally supported with respect to table 40. Bracket 77 is pivotally supported with respect to table 40 on a pin 78 extending through the table and into its upward extensions. The journalled portions of the shafts 71 and 72 are reduced so as to provide a shoulder bearing upon the upper surface bracket extensions 76 as shown in Figure 5. The extreme lower ends of the shafts 71 and 72 are provided with bevelled pinions 79 which mesh with spaced bevelled pinions 80 fixed to a cross shaft 81 journalled in downward extensions 82 of bracket 77. Both ends of the shaft 81 are squared to receive a crank 82 indicated in dotted lines in Figure 5.

It will be noted that by the above construction, rotation of shaft 81 will cause the threaded shafts 71 and 72 to simultaneously rotate with respect to the nuts 73 and 74 so that the entire superstructure may be raised or lowered, the links 61 to 63 holding the superstructure parallel to the surface of the supporting conveyor 30 and table at any point to which the superstructure may be elevated. The threaded drive included in the above gearing will rigidly hold the superstructure in any position.

The tray 22 upon which caps are placed by the operator for subsequent movement through the apparatus is flat with upstanding side walls and the inclined chute portion 23 through which the caps are moved by the operator to the disc 24 is rigid with the remainder of the tray. Tray 22 is normally in the position shown in solid lines in Figure 1, with its bottom wall resting upon upstanding elements 85 secured to the superstructure bars 58. In this position, the lower edge of the downwardly inclined outfeed portion 23 is immediately above the surface of the rotating disc 24 so that when the group of caps in the tray 22 is moved toward and down inclined chute 23, the caps will slide directly onto the disc. In order that the operating parts of the machine which are immediately beneath the tray 22 will be accessible for adjustment, the tray 22 is connected to the elements 85 by pairs of links 86. One end of each link is pivotally

connected to the associated upstanding element 85 as indicated in Figure 1 and the opposite end thereof is pivotally connected to a lug extending downwardly from the tray. The tray may thus be swung upwardly to the dotted line position shown in Figure 1, being maintained in this position by reason of the fact that the lower ends of one or more of the links 86 are lengthened to contact with a stop pin 87 provided on an upstanding element 85.

As best indicated in Figure 1, caps moving off the chain 26 are directed into the inclined chute portion 23 of passageway 21.

The cap applying mechanism generally designated by the numeral 29 and described in said original application Serial No. 351,004 is provided at the lower end of chute 23 as shown in Figure 3b.

In order to prevent the containers from being tilted backwardly by their initial engagement with the lowermost cap in the chute, we provide the centering and holding structure 31 described in detail in said application for Container Handling Apparatus filed of even date herewith. This structure is particularly desirable in the handling of full containers having a small base.

The container centering mechanism may be generally described as comprising two sets of driven belts 240 positioned on each side of the longitudinal center line of the container supporting conveyor 30. As best shown in Figure 1, each set of belts comprises an upper belt and a lower belt adapted to contact with a container at vertically spaced points on the side wall of the container.

Referring to Figures 3a, 3b, 4 and 5, the levelling and holding belt 32 and sealing belt 33 operate together, with the levelling belt surrounding the sealing belt as generally disclosed in said Stewart patent. The sealing belt 33 is of a construction similar to that disclosed in the Stewart patent and comprises pairs of links 270 and 271 pivotally supported from the plate 59 of the superstructure by the rod 69 and shaft 68, respectively.

As is fully described in said Stewart patent, the links 270 have a shaft 272 journalled at their lower ends which carries an idler sprocket 273 while the links 271 have a shaft 274 journalled between their lower ends to support a sprocket 275. Shaft 274 carries a smaller sprocket 276 which is driven by means of a sprocket chain 277 which extends upwardly to engage a corresponding sprocket wheel 278 on the shaft 68. Shaft 68 in turn carries a second sprocket driven by a chain 279 which encircles the sprocket wheel 280 on the shaft 65. As best shown in Figure 2, shaft 65 carries a pinion 280a which meshes with a pinion 281 on the shaft 56 and shaft 56 is driven from the speed reduction mechanism 51 through the drive chain 54.

Sprocket 275 drives the capping belt 33 to move the same about the idler sprocket 273. The lower ends of the links 270 and 271 are connected by a shoe 283 against the under surface of which the lower run of the capping chain 33 moves. The shoe 283 therefore holds the lower run of the chain in firm contact with the caps of containers moving beneath the same. The under surface of shoe 283 is downwardly bowed to a slight extent and is held in the position illustrated in Figures 3a and 3b by a spring 286 mounted upon a bolt 287 pivotally connected to the shoe as indicated at 288, one end of the spring bearing upon a bracket 289 fixed to the superstructure bars 60. As is fully described in said Stewart patent, a

container moving beneath the belt 33 may raise the shoe 283 slightly, but the only movement which the shoe can have is along a diagonal line extending upwardly toward the outfeed end of the capping chain 33. That is, the shoe and chain 33 will swing bodily about the pivots 68 and 69 and upwardly toward the outfeed end of the capping mechanism.

The levelling belt 32 is preferably of fabric or other bodily flexible material in order that the cap tops will not be marred by the same. Belt 32 moves about the pulley 200 positioned immediately adjacent the cap applying mechanism 29 and also about a pulley 34, with the major portion of its runs in contact with the corresponding runs of the capping chain 33. The pulley 200 is carried by a shaft 296 journaled in the bracket 201 and bracket 201 is pivoted upon a pin 297 extending through the lower end of a hanger 298 hooked over superstructure rod 69 and suitably held against swinging. In order that the pulley 200 may have a limited upward swinging movement on hanger 298, an arm 299 extends upwardly from bracket 201 between collars spaced on a stud 300 fixed to hanger 298. A spring may be provided behind the inner collar which is slideable on the stud. However, the outer collar is threaded upon the stud. The downward swinging movement of the bracket 201 carrying pulley 200 is limited by a bolt 301 threaded in the lower portion of bracket 298.

The above adjustable mounting of roll 200 will be so set that the lower run of belt 32 from roll 200 to the lower point of capping element 33 will be normally horizontal. Hence, roll 200 will be slightly lifted by an advancing cap and will therefore exert a downward holding force on the cap before the latter leaves the wiper 180, while belt 32 will exert a corresponding force until sealing occurs. In view of this, a cap cannot fall from a container and, in fact, the belt 32 will tend to actually level the cap upon the container mouth, that is bring its top wall parallel with the edge of the container mouth. This downward pressure also prevents the container from being upset.

The roll 34 at the outfeed end of belt 32 is rotatably mounted between the lower ends of a yoke 305 pivoted to the superstructure 57 at 306. Above the pivot point yoke 305 has a coil spring 307 connected thereto so that the roll 34 exerts tension upon the leveling belt 32. The tension of the spring 307 may be exerted by means of the adjusting arrangement generally indicated at 308. The fact that the lower run of belt 32 is held under tension by roll 34 causes the cap to be firmly held upon the container until it moves beneath the downwardly bowed portion of capping chain 33.

The leveling belt 32 is driven by means of its contact with the capping element or chain 33. Roller 35 is of sufficient weight to maintain the proper contact between the belt and the chain and is journaled in a yoke 311 pivoted on the superstructure at 312.

When the container moves beneath the downwardly bowed portion of the capping chain 33, shown at the right hand portion of Figure 3a, the cap will be moved to a firmly seated position upon the container due to the fact that the lower run of the capping chain is arranged at the proper height to squarely seat the cap upon a container of the minimum possible height of that particular size. Containers taller than this minimum height will act upon the lower run of chain 33, through belt 32, to lift

the shoe 283 to swing on the links 270 and 271 in a clockwise direction as viewed in Figures 3a and 3b against the action of the spring 286. In other words, the capping shoe 283 and in fact the entire capping chain, will move diagonally along a line inclined upwardly toward the outfeed end of the capping mechanism.

The fabric belt 32 moving at the same linear speed as the capping belt 33 insures that caps will not be marred by the metal links of the chain 33. In order that the belt 32 will be held properly centered upon chain 33 a pair of vertically mounted sheaves 315 are positioned adjacent the outfeed end of the belt. These sheaves are carried on links 316 horizontally pivoted at 317 upon the ends of downwardly projecting and adjustably mounted arms 318.

As best shown in Figure 1, the mouth 320 of a water jet pipe 321 may be positioned adjacent the outfeed end of each pair of centering belts 210 so as to remove from these belts any container contents which may drop upon them from an over-filled container.

It will be noted that all driven elements of the machine which contact with containers or caps move at the same speed with the possible exception of the disc 24 which supplies caps to the cap passageway 25. It is at least necessary that the centering and holding belts 210, container supporting conveyor 30, the levelling and holding belt 32 and capping chain 33 move at the same linear speed in order to prevent containers from being upset.

The terminology used in the specification is for the purpose of description and not limitation, the scope of the invention being indicated in the claims.

We claim:

1. The combination in a container capping apparatus, of a base, a container supporting conveyor movable on said base, a support above said conveyor, an endless belt capping element carried by said support and including a substantially horizontal run, a second endless belt of bodily flexible material movable about and with said first belt, a member pivoted on said base in advance of the infeed end of said first-named belt to move vertically with respect to said first belt, and a pulley journaled on said member to support the infeed end of said second belt.

2. The combination in a container capping apparatus, of a base, a container supporting conveyor movable on said base, a support above said conveyor, an endless belt capping element carried by said support and including a substantially horizontal run, a second endless belt of bodily flexible material movable about and with said first belt, a pulley at the outfeed end of said second belt carried by said support at a point spaced from the corresponding end of said first-named belt, a member pivoted on said base in advance of the infeed end of said first-named belt to swing vertically with respect to said first belt, and a pulley journaled on said member to support the infeed end of said second belt.

3. The combination in a container capping apparatus, of a base, a container supporting conveyor movable on said base, a support above said conveyor, an endless belt capping element carried by said support and including a substantially horizontal run, a second endless belt of bodily flexible material movable about and with said first belt, rotary means in advance of said first-named belt to support the infeed end

of said second belt, means to support said rotary means for upward vertical movement with respect to said first belt, an inclined cap chute adjacent the infeed end of said second belt, said cap chute including cap engaging means extending therefrom toward said second belt, said cap engaging means being of such length that a cap withdrawn from the chute by a container will be engaged by the infeed end of said second belt before moving out of contact with said cap engaging means.
